CLAIM

The ornamental design for a tire for a car, as shown and described.

DESCRIPTION

FIG. 1 is a perspective view of a tire for a car showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is an enlarged partial view between lines a-a', b-b', c-c' and d-d' from FIG. 2.

The evenly broken lines in the Figure-Drawings represent unclaimed environmental structure only and forms no part of the claimed design.

(Continued)

The dash dot dash lines in the Figure-Drawings represent unclaimed boundaries of the claimed design.

1 Claim, 8 Drawing Sheets
